UNITED STATES PATENT OFFICE

HERBERT S. ROSE, OF CHICAGO, ILLINOIS

WARM AIR REGISTER

Application filed March 8, 1929. Serial No. 345,300.

This invention relates to registers for warm air heating systems in houses and other buildings. It has for its object providing a register which will prevent the down draft of cold air through the register and conduit and, at the same time, will allow the cooler air adjacent the floor to be forced into the register and mixed with the warm air as it ascends, so as to more quickly heat and more thoroughly circulate the colder layers of air adjacent the floor.

Of the accompanying drawings, Fig. 1 is an elevation of a register which embodies the features of my invention; and Fig. 2 is a sectional view along the line 2—2 of Fig. 1.

My invention applies to any ordinary type of warm air register which is installed in the wall of the building adjacent the floor. The invention consists in providing openings 5 in the lower edge of the frame 6 which supports the open grille work 7 of the register. These openings are formed in the plate 8 which, in this instance, comprises the lower portion of the framework, but may be an independent plate if desired, and the plate has fixed thereto, in any suitable manner, an inner imperforate baffle plate or flange 9 which extends upwardly, as indicated, substantially to the lower portion of the openings 10 in the grille work. The shutter 11 which is adapted to open and close the grille work is in no way interfered with by the flange 9 and operates in the ordinary manner. When the shutter is closed, however, there is a passageway 12 for air, so that a slight amount of warm air can pass upwardly through the conduit 13, and, thence, into the room through the passageway 12 and the openings 5. In this manner, there is less tendency for a down draft of cold air being produced when the shutter is opened. The slight draft, produced by the passageway 12 and the openings 5, keep the air in the conduit warm and the down draft is prevented.

However, the principal object of my invention is to provide means for allowing cool air adjacent the floor 14 to pass into the openings 5, when the shutter 11 is raised, and to pass upwardly through the passageway 12 and mix with the uprising column of warm

air. As the stream of warm air passes upwardly through the conduit 13 and out of openings 10, a so-called suction is produced across the passageway 12 by the pressure of the air in the room, and this pressure tends to force the layer of cool air through the openings 5 and upwardly through the passageway 12. In this manner, the circulation of the air in the room is improved and the cooler layers of air adjacent the floor are constantly being replaced by warmer air.

I claim as my invention:

A vertically mounted warm air register having a grille and a vertically mounted plate adjacent the lower edge of the grille, said plate having an elongated horizontal narrow slot therethrough, and a second plate fixed to the lower edge of said first mentioned plate and projecting inwardly and upwardly to a line much nearer to the grille than to the slot or to the said lower edge, said second plate extending substantially the full length of said grille.

In testimony whereof, I hereunto set my hand.

HERBERT S. ROSE.
